COMBINED SITZ BATH AND BIDET

Pearl Howard, 1951 Selby Ave., Los Angeles, Calif.

Filed Mar. 29, 1963, Ser. No. 74,215

Term of patent 14 years

(Cl. D4—4)

FIG. 4.

FIG. 5.

FIG. 6.

FIG. 7.

FIG. 1 is a top plan view of a combined sitz bath and bidet showing my new design;

FIG. 2 is a side elevational view;

FIG. 3 is a bottom plan view thereof;

FIG. 4 is a front elevational view thereof;

FIG. 5 is a rear elevational view thereof;

FIG. 6 is a sectional view thereof, taken on line 6-6 of FIG. 1; and

FIG. 7 is a sectional view thereof, taken on the line 7-7 of FIGURE 1.

I claim:

The ornamental design for a combined sitz bath and bidet, substantially as shown.
